UNITED STATES PATENT OFFICE.

D. STANLEY HILL, OF EFFINGHAM, ILLINOIS.

ARTICULATOR FOR ARTIFICIAL DENTURES.

Application filed October 3, 1923. Serial No 666,217.

This invention relates to artificial dentures and has particular reference to improvements in an articulator for use in connection with preparing and properly positioning the teeth 5 in the plates.

One of the objects of the present invention is to provide an improved form of articulator by means of which the proper articulation of the teeth can be more efficiently and accurately accomplished.

A still further object of the invention is to provide an improved device which will not only facilitate the dentist's work in connection with preparing artificial dentures but will also obviate the necessity of making repeated fittings of the bite plates on the patient.

A still further object of the invention is to provide an improved adjustable articulator by means of which the occlusal path may be changed so as to vary the height of the bite of the artificial dentures.

25 A still further object of the invention is to provide an improved adjustable articulator by means of which longer or shorter teeth may be used on models without the necessity of removing the molds from the supporting bows.

30 A further object of the invention is to provide an adjustable device by means of which a mistake made in taking the original bite can be corrected without the necessity of removing the bite plates and taking a new bite.

These and other objects are accomplished by providing an improved form of articulator and in the construction and arrangement of the various parts in the manner hereinafter described and particularly pointed out in the appended claims.

40 Referring to the drawings, Fig. 1 is a top plan view of an articulator showing my improvement embodied therein.

Fig. 2 is a front elevational view of the articulator shown in Fig. 1 showing the position of the molds or models in dotted lines and showing the manner in which the teeth are articulated.

Fig. 3 is a side elevational view of my improved articulator showing the manner in which the upper bow may be swung upwardly to the position shown in dotted lines.

Fig. 4 is a rear elevational view of my improved articulator showing the means for adjusting the upper frame with respect to the base.

Fig. 5 is a cross sectional view of the securing means taken on the lines 5-5 in Fig. 4.

Fig. 6 is a cross sectional view taken on the lines 6—6 in Fig. 3, and

Fig. 7 is a cross sectional view of the adjusting means taken on the line 7-7 in Fig. 4.

For the purpose of illustration I have shown my improved form of articulator comprising a main base member 10 having upwardly and vertically extending guiding members 11 formed integrally therewith and positioned on the opposite sides thereof. 65

Located centrally of the main base member 10 and formed integrally therewith is a post 12 having a threaded bore 13 for the purpose hereinafter set forth. Positioned on the opposite sides of the post 12 and formed integrally with the base member 10 are socket portions 14 which are adapted to receive the mold supporting member or bow 15 therein by means of clamping members 16. The mold supporting member 15 comprises two converging arms 17 having an inclined plate 18 formed integrally with these arms as clearly shown in Fig. 1. Adjustably mounted on the base member 10 is a frame 19 which

ed on the base member 10 is a frame 19 which extends parallel to the base 10 and has formed on its outer sides thereof downwardly extending slide or guide members 20 which are adjustably connected to the vertically extending guiding members 11 of the base 10 in the manner hereinafter described. Formed integrally with the frame member 19 and intermediate the ends thereof is a downwardly projecting portion 21 having a recess 22 extending longitudinally therethrough. Adjacent one side of the recess 22 and extending rearwardly therefrom is an ear 23. Secured to the ear 23 by means of a clamping member 24 and a screw 25 is a flat spring 26. The flat spring 26 is curved

around at its upper end in a manner to engage the upper surface of a pivoted frame or bow supporting member 27 as clearly shown in Figs. 1, 2 and 4. The frame 27 has secured on its outer ends thereof adjustable pins 28. The lower ends of the pins 28 are pivotally mounted in concave sockets 29 formed in the outer ends of the adjustable frame 19 adjacent the guiding members 20. Formed on the outer ends of the pivoted frame 27 and forwardly of the adjustable pins 28 are inverted concave bearing portions 30 which are adapted to slidably engage adjustable pins 31 secured in the adjustable 100 105 110

frame 19. From the above description it will be seen that as the pivoted frame is swung from the full line position shown in Fig. 3 to the dotted line position, the frame is 5 swung about the lower ends of the pins 28 in the concavity 29 of the frame 19 as its pivot and that in the event the frame 27 is swung laterally the inverted concavity 30 of the frame 27 slidably engages the tops of the adjustable pins 31. The curved portion of the spring 26 which frictionally engages the central upper surface of the frame 27 normally retains the frame in its operative position and thereby prevents disengagement of the 10 frame 27 from the adjustable frame 19. Detachably secured in sockets 32 of the pivoted frame 27 by means of clamping screws 33 is an upper mold supporting member or bow 34. The mold supporting member or bow 15 comprises two oppositely converging arms 35. Formed integrally with and on the free ends of the arms 35 is a downwardly extending boss 36 which is provided with a longitudinally extending bore 37. Adjustably 20 mounted in the bore by means of a thumb screw 38 is a normally vertical post 39. The post 39 is provided with a series of graduations 40 adjacent the boss 36 which are preferably millimeters. Intermediate the ends 25 of the posts 39 is an annular groove 41. The groove 41 normally locates the pointer 42 in the occlusal plane by means of a thumb screw 43 which extends through the rear of the pointer and engages the groove. On both 30 sides of the pointer I have provided a plurality of graduations 44 on the post 39 which are preferably millimeters. The free or lower end of the post 39 is adapted to engage and contact with the inclined plate 18 of the 35 lower bow 15.

The essential feature of my improved articulator is in the provision of means for adjusting the bite by means of which the upper mold supporting member may be 40 adjusted with respect to the base. This mechanism comprises the hereinbefore described guiding members 11 and 20 of the base 10 and frame 19, respectively. The guiding members 11 are adapted to be slidably connected in a groove 45 extending longitudinally in the guiding members 20. The groove 45 of the guiding members 20 has oppositely bevelled surfaces 46, as clearly 45 shown in Fig. 5, which are adapted to engage corresponding bevel surfaces of the guiding members 11. When the proper adjustment of the adjustable frame has been secured these guiding members are locked against relative adjustment by means of thumb screws 47, which are in threaded engagement 50 with the guiding members 11. This locking action is secured by having the threaded portion of the thumb screws engage in the threaded aperture 48 of the guiding member 11 and with washers 49 contacting the outer

surfaces of the guiding members 20 in such a manner that the bevel surfaces 46 of the guiding members 20 are clamped between the washers 49 and the guiding members 11. The guiding members 11 and 20 of the base 55 member 10 and the frame member 19, respectively are provided with, on their outer sides thereof, corresponding graduations 50 and 51. These graduations are preferably in millimeters to correspond with the graduations on the post 39. The means for adjusting the frame 19 comprise a thumb screw 52 having its lower end threaded as shown at 53 and in threaded engagement with the bore 18 of the post 12. The upper end of the thumb screw 52 extends into a bore 54 formed in a boss 55 of the adjustable frame 19. The thumb screw 52 is rotatably secured in the boss 55 by a set screw 56 which engages an annular groove 57 formed in the upper end 60 of the thumb screw 52, as clearly shown in Fig. 7.

From the above description, it will be seen that as the thumb screw 52 is adjusted the frame 19 will be accordingly adjusted with respect to the base and that when the proper adjustment has been attained the thumb screws 47 are adjusted so as to lock the guiding members 11 and 20 of the base member 10 and the adjustable frame 19, respectively, against 95 relative movement.

I have shown and described a single form of guiding members by means of which the adjustable frame is guided in its adjustment with respect to the base, but it will, of course, be understood that various other forms of guiding members, such for instance, as telescoping members or the like, may be employed and still be within the spirit of my invention and that also various other forms or means for adjusting the adjustable frame with respect to the base may be employed and still be within contemplation of my invention.

In the operation of the above articulator, it will be understood that when it is desired to raise the bite, for example two millimeters, the thumb screws 47 are loosened and the thumb screw 52 adjusted until a variation of two millimeters in the graduations 50 and 51 of the guiding members 11 and 20 respectively, is attained, then a corresponding adjustment of two millimeters on the post 39 is made. This is done by loosening the thumb screw 38 and lowering the post two millimeters as shown by the graduation 40 adjacent the boss 36. Then in order to locate the occlusal plane the pointer is raised one millimeter on the graduation 44 of the post 39. It will of course be understood that if it is desired to lower the bite the operation is just reversed. This adjustment obviates the necessity of removing the models when longer teeth are used by merely adjusting the bite to correspond with the length of the teeth. 130

On the other hand, if the space is too great between the teeth the bite may be lowered and thereby also obviate the necessity of removing the models or molds from the bows.

5 In order that the adjustable parts may be readily returned to their normal positions I have provided zero graduations on the post 39 as well as on each of the guiding members 11 and 20 of the base 10 and frame 19, respectively.

10 From the above description, it will be seen that I have provided a very simple and efficient form of articulator and one in which the proper articulation is readily and accurately 15 accomplished through the means of my improved adjustable construction.

While in the above specification I have described one embodiment which my invention may assume in practice, it will be understood 20 that the same is capable of modification and that modification may be made without departing from the spirit and scope of my invention as expressed in the following claims.

25 What I claim as my invention and desire to secure by Letters Patent is:

30 1. An articulator comprising a base, a mold supporting member secured thereto, a frame mounted for vertical adjustment on said base, a second mold supporting member pivoted to 35 said frame, corresponding graduations carried by said base and frame, a post carried by said frame having graduations corresponding to those on said frame and base whereby said frame and post may be adjusted to raise or lower the plane of the bite, and means for securing said frame against movement with respect to said base.

40 2. An articulator for artificial dentures comprising a base, a mold supporting member secured thereto, a frame adjustably supported by said base having a mold supporting member secured thereto, a post adjustably secured to said last mentioned mold supporting member and engageable with the mold

45 supporting member on said base, means for adjusting said adjustable frame and said post whereby one of said mold supporting frames may be adjusted bodily with respect to the other, graduations on the sides of said base and frame respectively for ascertaining the 50 movement of said frame with respect to said base, and graduations of like dimensions formed on said post for determining the adjustment of said post with respect to said last mentioned mold supporting member to 55 compensate for the adjustment of said frame with respect to said base in a manner to properly position the dentures with respect to each other.

3. In an articulator for artificial dentures, 60 the combination of a base having guide members formed thereon, mold supporting arms secured to said base, a frame slidably mounted on said guide members, a mold supporting bow carried by said frame, means for adjusting said frame and bow with respect to 65 said base and arms, a post adjustably mounted in said bow, a pointer adjustably mounted on said post for indicating the occlusal plane of said dentures, co-operating graduations of 70 predetermined dimensions formed on said guide members and said frame respectively for ascertaining the amount of movement of said frame with respect to said base, and graduations of like dimensions formed on said 75 post for determining the amount of movement of said post with respect to said bow, and for determining the relative movement of said pointer with respect to said post in a manner to position said pointer in the proper 80 occlusal plane of said dentures when said frame and mold supporting bow are adjusted with respect to said base and mold supporting arms.

85 In testimony whereof I have signed my name to this specification on this fifteenth day of September, A. D. 1923.

D. STANLEY HILL.
